A. C. GILBERT

TOY VEHICLE

Filed Aug. 27, 1919

UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

TOY VEHICLE.

Application filed August 27, 1919. Serial No. 320,297.

To all whom it may concern:

Be it known that I, ALFRED C. GILBERT, a citizen of the United States, residing at New Haven, in the county of New Haven and State of Connecticut, have invented certain new and useful Improvements in Toy Vehicles, of which the following is a full, clear, and exact description.

This invention relates to means for connecting an axle of a vehicle to the body portion of the same, and more particularly to resilient means for connecting the axle of a toy vehicle to the body portion of the same.

One object of my invention is to provide a novel spring construction designed to be positioned between the body portion of a vehicle and an axle supporting the same, the spring being so constructed that it forms a very satisfactory means for securing the axle to the body portion of the vehicle, while at the same time it reduces the jolts and jars to which the vehicle body is submitted.

Another object of my invention is to provide simple but satisfactory means for adjustably securing a spring to an axle of a vehicle.

To these and other ends, the invention consists in the novel features and combinations of parts to be hereinafter described and claimed.

In the accompanying drawing,

Fig. 1 is a side view of a child's wheeled toy embodying my invention, the near rear wheel being removed;

Fig. 2 is a front view of the device shown in Fig. 1;

Fig. 3 is an enlarged view of a detail showing the means for securing a spring to its axle;

Fig. 4 is a top plan view of the parts shown in Fig. 3, the spring being broken away diagonally; and

Fig. 5 is a vertical sectional view of a modification showing a somewhat different means for securing a spring to its axle.

In the drawing, I have illustrated my invention as applied to a child's wheeled toy of the type which comprises a seat or body member designed to be straddled by the child, the rear portion of the seat being supported by a pair of spaced rear wheels, while the front portion is supported by a

single wheel provided with means for steering the same. However, I do not regard my invention as limited in its application to the type of child's toy shown, since my invention is well adapted to be used upon various types of vehicles for connecting the axles to the body of the same.

In the embodiment of my invention illustrated, I have shown a seat or body member designated by the numeral 10, the same being somewhat rectangular in shape, with the forward portion narrower than the rear portion of the seat, in order that a child may conveniently sit on the same with his legs straddling the forward portion of the seat. This forward portion of the body member 10 is preferably provided with a steering post 11, the lower portion of which is preferably larger in diameter than the upper portion 12, whereby a shoulder is formed about midway between the ends of this post, upon which shoulder the lower face of the body member 10 preferably rests. The upper portion 12 of this post is preferably rotatably mounted in a circular hole formed through the forward end of the body member 10, as indicated by the numeral 13, and in order to prevent the post 11 from moving longitudinally through the body member, a collar or the like 14 is preferably mounted about the reduced portion 12, with its lower face engaging the upper face of the body member 10, and this collar is secured to the post 11 by a pin, or the like, 15. The lower end of the post 11 is preferably slotted, as at 16, in which slot the supporting wheel 17 is rotatably mounted by the bolt 18. In order that the child riding upon this toy may conveniently turn the post 11 in order to steer the vehicle, a relatively long pin 19 is preferably mounted in the upper end of the post to form handle bars, which may be grasped by the child in order to steer the vehicle.

The construction so far described forms no part of my invention, but my invention, as above stated, resides in the means for connecting an axle 20 to the seat or body member 10. In the embodiment shown, I have provided the body member 10 with two downwardly curved spring members 21. These spring members are preferably constructed out of relatively flat steel strips,

and one end of each of these springs is preferably secured to the under face of the seat member 10 by bolts 22, the springs being preferably spaced apart a considerable distance, as shown in Fig. 2. The means which I have provided for securing the lower end of each of these springs to the rear axle consist of a U-shaped clip 23 constructed to straddle the spring 21, and having circular holes formed through the spaced legs of this clip through which the axle 20 is inserted, the spring being firmly clamped against the axle 20 in any desired position of adjustment by tightening up the set screw 24, the inner end of which abuts against the outer face of the spring. Upon the opposite ends of the axle 20 may be mounted any desired type of wheels 25, these wheels being secured in place upon the axle by cotter pins 26, or by any other preferred securing means.

From the above description, when read in connection with the drawing, it will be seen that the springs 21 form a very satisfactory means for connecting the seat or body member 10 to the axle 20, while this seat is supported at the desired height above the supporting axle. It will also be apparent that the flexible springs 21 will, to a very large extent, relieve the seat 10 from the jolts and jars to which it would otherwise be submitted. Furthermore, it will be seen that the U-shaped clips 23 form a very satisfactory means for clamping the lower portion of the springs 21 to the axle 20. It is also obvious that the clips 23, in addition to clamping the springs 21 to the axle 20, also comprise the means whereby the axle is held against rotation and retained against sideways movement relatively to said body member 10.

In Fig. 5 of the drawing, I have shown a slightly modified construction for securing the lower portion of the springs 21 to the axle. In this construction, I have formed drill holes 27 through the spring 21', these drill holes being positioned to permit the set screw 24' to pass through the same when this set screw is tightened up, so that its inner end abuts against the axle 20. In this construction, the distance between the inner face of the clip 23' and the axle 20 should be substantially the same as the thickness of the spring 21', so that the spring will fit rather snugly between the axle and the inner rear wall of the clip. By providing a number of drill holes in the spring 21', the same may be secured to the axle 20 in any desired position of adjustment.

From the above description, it will be apparent that the mechanism herein described for securing an axle to the body portion of a vehicle is well adapted to be used upon various types of vehicles other than the device herein disclosed.

What I claim is:

1. In combination with a toy vehicle provided with a rigid body member, a front steering post and a supporting axle, means for securing the body member to the steering post and means for securing said axle to said body member, comprising a leaf spring rigidly secured to said body member with an end projecting therefrom, and a clamp provided with a set screw for rigidly clamping said spring to said axle. 75

2. The combination in a child's wheeled toy of the type provided with spaced rear wheels and a single steerable forward wheel, of a rigid body member constructed to form a seat, with an axle for said rear wheels, and a resilient leaf spring having one end secured to the under side of said seat and having its other end adjustably secured to said axle to support said seat upon said axle. 80 85

3. A child's vehicle, comprising a seat member, a steering post projecting vertically through the front part of said seat member and rotatably connected thereto, said steering post being provided with a ground engaging wheel at its lower end, a rear ground engaging structure comprising an axle and wheels mounted thereon, and a pair of rearwardly and downwardly directed leaf springs rigidly connected at one end with the seat member and at the other end to said axle for supporting said seat member resiliently from said axle. 90 95

4. A child's vehicle comprising a saddle-shaped seat member, a steering post passing vertically through said member and rotatably connected thereto, said steering post having a ground engaging wheel at its lower end, a rear axle having wheels upon the ends thereof, and a pair of rearwardly and downwardly curved leaf springs of the cantilever type secured at one end to the under-side of said seat, and secured at their other ends to the axle and supporting said seat directly from said axle in a resilient manner. 100 105 110

5. A child's vehicle provided with a seat member, a steering post passing vertically through said seat member and rotatably connected thereto, said post having a ground engaging wheel at its lower end, a rear axle having a ground wheel at each end thereof, and means for supporting said seat member from but at a substantial distance horizontally away from such axle in a resilient manner, comprising leaf springs of the cantilever type, each having one end rigidly secured to said seat member in a substantially horizontal position, and curved in approximately quadrantal shape and having its other end in an approximately vertical position secured flatwise against the side of said axle. 115 120 125

In witness whereof, I have hereunto set my hand on the 23d day of August, 1919.

ALFRED C. GILBERT.
